UNITED STATES PATENT OFFICE

KARL RICHARD LIEBERKNECHT, OF OBERLUNGWITZ, GERMANY

LACE ATTACHMENT FOR FLAT KNITTING MACHINES

Application filed August 1, 1930, Serial No. 472,269, and in Germany February 24, 1930.

This invention relates to a device for producing open work lace cloths or overall lace patterns on a flat knitting machine.

As is well known, the method of making open work lace designs on flat knitting machines, consists of removing loops from certain needles at certain times and transferring the loops to an adjacent group of needles at either the right or left side. The transferring of the loops results in the provision of holes or open spaces where the loops were removed and groups of such holes or open spaces comprise the design. The particular group of needles to be manipulated and the direction in which the loops are to be transferred are determined by a pattern and transferring device, which positions the transfer or lace points over the needles from which the loops are to be removed and after the loops are on the transfer points, they are shifted to either right or left a distance of one or more needles and at which point the loops are delivered by the transfer points to the receiving needles therefor.

There is considerable difficulty on fine gauge, multi-section machines, in the registering of the lacing or transfer points with the needles the course of temperature changes. It is one of the objects of this invention to overcome this difficulty by placing a number of relatively inexpensive pattern devices at various places along the length of the machine so as to reduce this temperature effect to a negligible amount.

Other objects of the invention include the provision of means for making lace cloths or patterns of wide design, the provision of means to move the lace points directly from one operating position to another without always returning to a neutral position, thereby permitting a greater speed of operation of the lace tackle and to mount the attachments on the machine in a manner to utilize existing supporting members and conserve space.

With the above and other objects in view that will become apparent as the nature of the invention is better understood, the same consists in the novel form, combination and

arrangement of parts hereinafter more fully described, shown in the accompanying drawings and claimed.

In the drawings:—

Figure 1 is a fragmentary diagrammatic front elevational view of a lace attachment for flat knitting machines;

Figure 2 is a side elevational view with certain shafts shown in cross-section;

Figure 3 is a fragmentary top plan view of the parts shown in Figure 2; and

Figure 4 is a fragmentary perspective view showing the cam to effect the dipping operation and the adjustable stop for regulating dipping.

It is to be understood that while but one such device may be used for a relatively short machine, two or more should be used and distributed over its length for a longer machine, in order to avoid temperature difficulties.

Referring to the drawings, the device consists of a lace attachment for flat knitting machines including a threaded spindle 1 supported by and turning in bearings 1a, fastened to a well known front covering or narrowing machine shaft 5, which in turn is supported as is usual on such machines, by the covering or narrowing machine arm 5a and from the cam shaft 2 by a system of rollers, levers and links, as is well known but not here shown in detail.

A traversing nut 7 is threaded on the spindle 1 and carries a projection engaged with the lace rod 3 and is secured to said rod for axially shifting the same by means of the two collars 3a, one positioned at each side thereof on the lace rod. The lace rod 3 is slidably mounted in brackets 5a fastened to the shaft 5. Lace fingers 4 are fastened to the lace rod 3, each carrying a lace point 4a that engage with any of the needles 2 within their traverse. It is of course understood that there are one or more lace fingers 4 for each needle section 2 and that each lace finger may have one or more lace points 4a.

A ratchet wheel 6 is keyed to the threaded spindle 1 and is selectively engageable by the rack portions 8' or 8" carried by a forked rack link 8. The other end of the rack link

8 is connected to a bell crank lever pivoted on the narrowing shaft 9 of the machine, the other end of the bell crank lever being connected by a link 9b and 9c to the cam lever 10. As is well known, the narrowing shaft 9 rocks as the shaft 5 dips for lace points 4a to engage the needles 2. To permit dipping of the narrowing machine with either rack portion 8' or 8" engaged with the ratchet wheel 6, without any rotation of the spindle 1 due to the different arcs described by the ratchet wheel 6 and rack portions 8' and 8", as they swing about the shaft 9, one end of each of the links 9b and 9c is pivotally connected to the cross head 9f sliding in brackets 9g fastened to the shaft 9. As a result of this arrangement, as the narrowing machine dips, toggle linkage of 9b and 9c is straightened out and the long end of 9a moved forwardly, motion of which is communicated to the rack fork 8 which results in engagement between the ratchet wheel 6 and the rack portion 8' or 8" of the fork which remains unchanged during vertical movement of the shaft 5. The cam lever 10 is pivoted on the stud 10a that is fixed to the machine frame and carries a roller 10b which is held against the cam 11 by means of the tensioned spring 10c. The peripheral edge of the cam 11 is provided with a recess 11' and said cam is mounted on the shaft α . As the cam rotates, the spring 10c pulls the roller 10b into the recess 11', thereby effecting maximum downward movement of the rack portions 8' or 8" which, communicated through the ratchet wheel 6 to the spindle 1 provides for a maximum traverse of lace points 4a over a definite and predetermined number of needles.

Beneath the cam lever 10, there is positioned a swinging stepped stop 12 pivoted on the stud 12a carried by the machine frame. The purpose of this stepped stop 12 is to limit the downward pull of the cam lever 10 by the spring 10c as the roller 10b leaves the high point of the cam 11. The particular step of the stop 12 to be engaged by the cam lever 10 is determined from a pattern chain that carries a row of buttons of various heights engaged with the stepped stop 12 by means of the connecting rod 13. The difference in height from one step to the next, when transferred through the mechanism shown, effect a shift of point from one needle to the next.

Pivottally connected to the leg portion of the forked rack 8 is a link 14 that is also pivotally connected at its other end to the cam lever 15, pivoted on stud 15a fixed to the machine frame, the cam lever 15 carrying a roller 18. A pair of adjacently positioned cams 16 and 17 is carried by the cam shaft α and the roller 18 carried by the cam lever 15 is maintained in engagement with either of said cams 16 or 17 by means of the

spring 15b. The roller 18 is slidably and rotatably mounted on a stud fixed to the lever 15 and is shifted by means of a fork 19 fastened to the rod 20 which in turn is shifted by means of a second row of buttons on a pattern chain. The cam 16 is provided with a projection by means of which the upper rack portion 8' is engaged with the ratchet wheel 6, whereas at the corresponding position of cam 17 there is a recess to bring the lower rack portion 8" into engagement with the ratchet wheel 6. The length of these projections and recesses is so chosen that the racks only engage the ratchet wheel 6 during the time the spindle is being turned. To provide for transferring either right or left after lace points have picked up the loops, a third row of buttons on a pattern chain shifts the roller 18 by means of rod 20 and fork 19 to either cam 16 or 17 a second time just before transferring and engages either the second projection or recess, depending on which cam roller 18 rides upon.

The operation of the device is as follows:

To begin lacing, the roller 18 and stepped stop 12 synchronized with the pattern chain are set for the first dip. When the parts are so related, the roller 18 will ride on either cam 16 or 17, depending in which direction the lace point is to be traversed. If the cam 16 is engaged, the rack portion 8' will be engaged with the ratchet wheel 6, and if cam 17 is engaged, the rack portion 8" will engage the ratchet wheel 6. As the rack engages the ratchet wheel 6, the recess 11' on the cam 11 permits the spring 10c to pull the lever 10 against a step of the stop 12 as selected by a button on the pattern chain, thus effecting the traverse of the nut 7 engaging the spindle to either the right or left a distance corresponding to the depth of the step on the stop 12. As the nut 7 engages the lace rod 3, which in turn carries the lace points 4a, the latter are positioned over the needles which are to be manipulated. The racks are then disengaged from the ratchet wheel 6 as the roller 18 rides on the outer edge of cam parts 16 and 17 and returns disengaged to a starting position as the roller 10b rides on the outer part of the cam 11. During this disengagement and the return of the racks, the covering or narrowing shaft 5 is caused to dip with the result that the lace points engage and remove the loops from desired needles, and ascend sufficiently to permit their transfer laterally without interference as is well understood. Immediately prior to transferring, the roller 18 is again shifted by means of a button on the pattern chain to ride on either cam 16 or 17 which brings into operation either the upper rack portion 8' or the lower rack portion 8", depending on whether loops are to be transferred to the right or left adjacent group of needles and then, by means of the

recess 11" of the cam 11, the rack 8 is given a forward push to turn the spindle sufficiently so that the nut thereon is traversed a distance of one or more needles, depending 5 on the extent of the transfer. In the event that the design is such that the space between the two lace holes in one course is greater than the maximum stroke of the rack during one lacking cycle, it is possible 10 by two or more false lacing cycles (dipping, removing loop, but replacing loops on same needle without transferring) to effect such extreme operating positions of lacing points.

From the above detailed description of 15 the invention, it is believed that the construction and operation thereof will at once be apparent, and while there is herein shown, and described the preferred embodiment of the invention, it is nevertheless to be understood, that minor changes may be made 20 therein without departing from the spirit and scope of the invention as claimed.

I claim:

1. In a flat knitting machine, a pattern 25 position and transferring device for effecting lace work designs comprising in combination, a threaded spindle, a nut working on the threaded portion of the spindle, a supporting arm connected to the nut, a lace 30 rod to which the supporting arm is attached, a ratchet wheel on said spindle, a double rack adapted to intermittently mesh with

either side of said ratchet to effect a lateral shifting of said nut and said lace rod, a cam shaft parallel with the spindle, a cam on said shaft, a tensioned lever pivoted on the machine and carrying a roller working on the cam, said lever being operatively connected with the double rack for reciprocation of said double rack, a pair of smaller cams on the cam shaft adapted to intermittently bring one of said racks into meshing engagement with the ratchet wheel and a stepped stop shiftably mounted in the path of movement of the tensioned lever for regulating the thrust movement of said rack. 70 75

2. In a flat knitting machine, a pattern position and transferring device for effecting lace work designs comprising in combination, a threaded spindle, a nut working on the threaded portion of the spindle, a supporting arm connected to the nut, a lace rod to which the supporting arm is attached, a ratchet wheel on the spindle, a double rack intermittently engageable with the ratchet wheel, cam operated means for effecting reciprocation of the double rack, cam operated means for intermittently bringing one of said racks into meshing engagement with the ratchet wheel and a stepped stop cooperating with the means for effecting reciprocation of the double rack to control the length of reciprocation. 80 85 90 95
